UNITED STATES PATENT OFFICE.

HARRY H. VICKERS, OF CORONA, NEW YORK, ASSIGNOR TO UNDERWOOD TYPEWRITER COMPANY, OF NEW YORK, N. Y., A CORPORATION OF DELAWARE.

TYPEWRITING MACHINE.

Application filed August 23, 1921, Serial No. 494,612. Renewed August 22, 1922. Serial No. 583,584.

To all whom it may concern:

Be it known that I, HARRY H. VICKERS, a citizen of the United States, residing in Corona, Long Island, in the county of 5 Queens and State of New York, have invented certain new and useful Improvements in Typewriting Machines, of which the following is a specification.

This invention relates to sheet-collating 10 means, and is in the nature of an improvement on the application of J. A. B. Smith, Serial No. 476,422, filed June 10, 1921.

In said application, provision is made of 15 sheet-controlling means for use in work in which data, typed on statement-sheets and ledger-sheets, is recorded upon a single record-sheet which is of considerable length and is left in the machine while statement-sheets and ledger-sheets relating to accounts of 20 different customers are inserted, typed upon and removed. The statement-sheet and ledger-sheet are inserted at the front of the platen and collated on the table beneath which the record-sheet is directed. In the 25 collating operation, the statement-sheet and the ledger-sheet, which is usually wider than the former, are adjusted with their left edges against the left side-edge gage, and the ledger-sheet is clamped in position 30 beneath the statement-sheet by a clamp at the left edge of the collating table, the engaging portion of the clamp being flat, so as to lie between the two sheets and having a very slight movement to and from effective 35 position so as not to interfere with the statement-sheet. The clamp-operating means extends a substantial distance to the left of the left side-edge gage and necessitates a loss of space at that side of the collating table, 40 one effect being to prevent the left auxiliary feed-roll for the record-sheet from being placed as close to the gage as desired.

According to the present invention, provision is made of an improved clamp and 45 clamp-operating means by which such sacrifice of space is obviated.

In the embodiment of the invention herein disclosed, a flat engaging finger extends inwardly, through an aperture in the left 50 side-edge gage, from the lower edge and the forward end of a lever pivoted intermediate its ends on the side-edge gage. The other end of the lever is slotted to receive a cam or eccentric, which may be turned by a suit-

able finger-piece or handle to actuate the 55 clamp or to release it.

Provision may be made of a plate secured to the left side-edge gage, and the lever, cam and handle may be held substantially flat along the outside of said plate. Adjacent the handle, the plate may have a downward projection in the form of a sector having the pivot of the handle as its center and provided with a stop at its lower edge to limit the downward movement of the handle. 65

Other features and advantages will hereinafter appear.

In the accompanying drawings,

Figure 1 is a front view, showing the invention applied to so much of the platen-frame of an Underwood standard typewriter 70 as is necessary for the purpose of illustration.

Figure 2 is a vertical section, taken along the line 2—2 of Figure 1, looking in the direction of the arrows, and shows the clamping device in ineffective condition.

Figure 3 is a fragmentary view similar to Figure 2, but showing the clamping device effective to hold the ledger-sheet against the 75 collating table.

Figure 4 is a fragmentary perspective view, showing the ledger-sheet clamped on the collating table.

A platen 11 is mounted on an axle 12 journaled in the ends 13 of a platen-frame 14, which comprises a rear paper-table 15 and a rod 16 connecting the ends 13.

To support the collating device above the platen, brackets 17 are secured on the tops of the ends 13 of the platen-frame by suitable means, such as screws 18, and connected by rods 19 and 20 engaging grooves 21 and 22, respectively, of plates 23 pivotally mounted on the rod 16. It will be seen that the rods 19 and 20 serve to prevent rotation of the plates 23 about the rod 16. Attached to lugs 24, extending leftwardly from each of the plates 23, by screws 25, is a bar 26 on which are mounted sections 27 and 28 of a collating table designated in general by 90 29. Preferably, the sections 27 and 28 are secured to the bar 26 by screws 27^a extending through slots 28^a and threaded into the bar, the sections 27 and 28 being countersunk at 95 29^a around the slots, so that the heads of the screws 27^a will lie beneath the front surfaces of the sections 27 and 28, and, conse-

100

105

quently, will not be engaged by the edges of the work-sheets.

When the machine is in use, a record-sheet 30 of considerable length is passed over the rear paper-table 15 and between the platen and usual feed-rolls 31, past the printing point, and upwardly along the collating table 29. It should be understood that during such insertion the feed-rolls 31 are in cast-off position. Since, however, the statement-sheets and ledger-sheets are to receive only the usual single line of typing at each insertion, it is found convenient to insert the same at the front of the platen. For this purpose, provision is made at the right of the machine of a directing member or guide 32, having a groove 33 at its rear edge into which the forward edge of the paper-table 15 is moved when the latter is shifted to the right by means of the typewriter-carriage. If then the ledger-sheet 34 and the statement-sheet 34^a are passed downward between the platen and the member 32, when the carriage is at the right of the machine, they will, if of sufficient length, be guided by the member 32 between the forward edge of the rear paper-table 15 and the platen. After adjusting the ledger-sheet 34 with the assistance of the left side-edge gage 35 on the section 27, it may be clamped in position on the collating table and detained there until adjustment of the statement-sheet 34^a has been effected. A right side-edge gage 36 may be provided on section 28. The structure thus far described is substantially the same as that disclosed in said application of Smith.

For the purpose of clamping the ledger-sheet 34 on the section 27, provision is made of a flat finger 37 extending through an aperture 38 in the side-edge gage 35 just above the upper face of the support or section 27 and substantially parallel to the latter. At its outer end, the flat finger 37 is connected with the lower edge of the forward end of a flat lever 39, mounted on a screw or pivot 40 on a plate 41, secured to the side-edge gage 35 by means of screws 42. The lever 39 lies flat against the plate 41 and takes up very little room to the left of the gage 35. To control the movement of finger 37 to and from effective position, provision is made of an eccentric or cam 43, mounted on the plate 41 by means of a screw or pivot 44 and so positioned relatively to the operating arm 44^a that, when the arm 44^a is moved to the Figure 2 position determined by a stop 45 on a sector 46, which may form part of the plate 41, the finger 37 will be shifted to ineffective position. The plate 41 with the sector 46 and stop 45 forms a convenient support for the movable parts of the clamping device and serves as means by which application of the device to collating tables in use may be facilitated. It will be seen

that the lever 39 is bent inwardly at the lower end of the plate 41, so that its lower end will lie close to the gage 35. As will be seen upon inspection of Figure 2, the cam 43 in the position shown in that figure will be entirely ineffective for sheet-clamping, but, when swung in a clockwise direction by means of the arm or handle 44^a, the cam will operate to shift the upper end of the lever 39 until the handle reaches the Figure 3 position in which the lever and finger 37 will be locked in effective position.

It will be seen that the finger 37 may readily be shifted to and from effective position by means of the handle 44^a, and, that, due to the compactness of the controlling device for the finger 37, the left-hand roll of the auxiliary rolls 47 to engage the record-sheet may be positioned close to the left side-edge gage 35, a result which could not be obtained in the structure disclosed in said application of Smith.

The rolls 47 are pivotally mounted in brackets 48, carried by a shaft 49 in bearings 50 on the ends 13 of the platen-frame, and the rolls 47 are yieldingly urged towards the platen by springs 51, one for each bearing attached thereto at one end and at the other end to the shaft 49. To withdraw the auxiliary rolls from the platen, provision may be made of a finger-piece 52 fixed on the shaft 49 and of a spring detent 53 to engage and yieldably hold the finger-piece 52 when the latter is swung rearwardly to withdraw the rolls 47. The means for supporting and controlling the rolls 47 are substantially the same as those disclosed in said application of Smith. When the statement-sheet 34^a and the ledger-sheet 34 corresponding to a customer's account have been adjusted over the record-sheet 30 with carbon-sheets interleaved therebetween, typing may be effected in the usual manner by types 54 on type-bars 55.

Variations may be resorted to within the scope of the invention, and portions of the improvements may be used without others.

Having thus described my invention, I claim:

1. A collating device comprising, in combination, a sheet-supporting member, a side-edge gage projecting therefrom, a lever extending along the outer side of the gage and pivotally supported thereon, and a clamping device including a flat finger substantially parallel to said member and extending from the lower edge of the lever at its front end through an opening provided therefor in the gage.

2. A collating device comprising, in combination, a sheet-supporting member, a side-edge gage projecting therefrom, a lever extending along the outer side of the gage and pivotally supported thereon, a clamping device including a flat finger extending from

the lower edge of the lever at its front end through an opening provided therefor in the gage, and means to actuate said lever including a pivotally mounted eccentric fitting in a slot extending longitudinally of the lever.

5. A collating device comprising, in combination, a sheet-supporting member, a side-edge gage projecting therefrom, a lever extending along the outer side of the gage and pivotally supported thereon, a clamping device including a flat finger extending from the lower edge of the lever at its front end through an opening provided therefor in the gage, means to actuate said lever including a pivotally mounted eccentric fitting into a slot extending longitudinally of the lever, and an operating handle for said eccentric.
10. 4. A collating device comprising, in combination, a sheet-supporting member, a side-edge gage projecting therefrom, a lever extending along the outer side of the gage and pivotally supported thereon, a clamping device including a flat finger extending from the lower edge of the lever at its front end through an opening in the gage, and means including a cam for shifting said lever.

5. A collating device comprising, in combination, a sheet-supporting member, a side-edge gage projecting therefrom, a flat member secured to the outer side of said gage, a lever pivoted on said member, a flat lever lying along said gage, and a flat finger substantially parallel to said member and extending from the front end of the lever through an opening in the gage adjacent said supporting member.

6. A collating device comprising, in combination, a sheet-supporting member, a side-edge gage projecting therefrom, a flat member secured to the outer side of said gage, a lever pivoted on said member, a flat lever having a flat finger extending from its front end through an opening in the gage adjacent said supporting member, and manually-operable actuating means mounted on said flat member.

7. A collating device comprising, in combination, a sheet-supporting member, a side-edge gage projecting therefrom, a flat member secured to the outer side of said gage, a stop on said flat member, a lever pivoted on the outer side of said member and limited in its movement by said stop, a flat finger extending through an opening in said gage adjacent said supporting member, and operating means for said lever mounted on said flat member.

60. 8. A collating device comprising, in combination, a sheet-supporting member, a side-edge gage projecting therefrom, a flat finger to engage said supporting member adjacent the gage, and controlling means for said finger mounted on the outer side of the gage,

comprising members movable substantially in a plane parallel to the outer face of the gage so as to economize space laterally of the gage.

9. In a typewriting machine, in combination, a platen, a platen-frame, a collating table above said platen, a side-edge gage on one edge of said table, auxiliary rolls to hold against the platen, on opposite sides of the table, a record-sheet passed between the platen and the lower edge of the table, and means to clamp a work-sheet on said table, comprising a flat clamping finger substantially parallel to the table and extending through an opening in the gage adjacent the table, a finger-supporting lever extending along the outer side of the gage and pivotally supported thereon, and actuating means for said lever to move said finger to clamping position and slightly away therefrom, comprising a member supported at the outer side of said gage and movable in a plane substantially parallel to the gaging surface of said gage, whereby the auxiliary roll at the adjacent end of the platen may be positioned close to said gage.

10. In a typewriting machine, in combination, a platen, a platen-frame, a collating table above said platen, a side-edge gage on one edge of said table, auxiliary rolls to hold against the platen, on opposite sides of the table, a record-sheet passed between the platen and the lower edge of the table, and means to clamp a work-sheet on said table, comprising a flat finger to engage the sheet when gaged by said side-edge gage and to permit another sheet to be gaged thereover, and operating means for said finger extending along the outside of said gage and close thereto so that the adjacent auxiliary roll may be positioned close to said gage.

11. In a typewriting machine, in combination, a platen, a platen-frame, a collating table above said platen, a side-edge gage on one edge of said table, auxiliary rolls to hold against the platen, on opposite sides of the table, a record-sheet passed between the platen and the lower edge of the table, and means to clamp a work-sheet on said table, comprising a flat finger to engage the sheet when gaged by said side-edge gage and to permit another sheet to be gaged thereover, said finger being substantially parallel to said table and extending through a narrow slot in said gage adjacent the upper surface of said table, and movement of said finger being limited so that when raised it will not interfere with the work-sheet placed thereover, and operating means for said finger supported on said gage and having its elements movable substantially in the plane thereof so as to enable the adjacent auxiliary roll to be placed close thereto.

12. In a typewriting machine, in combination, a platen, a platen-frame, a collating

- table above said platen, a side-edge gage at one edge of said table, auxiliary rolls to press against the platen, on opposite sides of the table, a record-sheet, and means to 5 clamp a work-sheet on said table adjacent said gage, comprising a flat finger extending through said gage and having a movement toward and from said table, so slight as not to interfere with a work-sheet passing there- 10 over, and finger-actuating means comprising members supported at the outside of said gage and movable substantially in planes parallel to said gage, so that the auxiliary roll at the adjacent end of the platen may 15 be positioned close to said gage.
13. A collating device comprising, in combination, a sheet-supporting member, and a clamping device pivoted to swing about an axis parallel to the platen-axle, co-operat- 20 ing with the sheet-supporting member to clamp a sheet and to permit another sheet to be gaged by a gage on the collating device while the clamping device is in clamp- 25 ing position.
14. A collating device comprising, in combination, a feed-roll, a sheet-clamping member alongside said feed-roll in close proximity thereto, and means extending upward from the clamping member to swing the clamping member whereby the clamping member may be operated without interfering with the feed-roll.
15. A collating device comprising, in combination, a sheet-supporting member, an edge gage, a clamping member pivotally mounted on the edge gage to swing in a path substantially parallel to the edge gage, and means mounted on the edge gage for operating the clamping member.
16. A collating device comprising, in combination, a sheet-supporting member, an edge gage projecting therefrom, a lever pivoted to said edge gage to swing in a plane parallel to the gage and having a clamping face formed upon it, and means mounted on the edge gage to operate the lever.
17. A collating device comprising, in combination, a sheet-supporting member having an edge gage projecting therefrom, a clamp-

ing member for co-operation with the sheet-supporting member, a lever for moving the clamping member to and from clamping position, and means on the edge gage to limit the movement of the lever in the direction to carry the clamping member away from clamping position.

18. A collating device comprising, in combination, a sheet-supporting member, an edge gage, and means to clamp a sheet of paper upon the supporting member, includ- 60 ing a thin plate lever having one end bifurcated and slightly offset and the other end slightly offset in the opposite direction and formed with a plate-like clamping extension 65 at right angles to the main body of the lever, said lever being pivoted intermediate its ends upon the edge gage.

19. A collating device comprising, in combination, a sheet-supporting member, an edge gage, and means to clamp a sheet of paper upon the supporting member, consisting of thin plate-like members mounted on the edge gage for swinging movement 70 in paths which are parallel to the edge 75 gage.

20. A collating device comprising, in combination, a sheet-supporting member, an edge gage, a lever carrying a clamping member, mounted on the edge gage, and means 80 for positively controlling the movement of the lever to and from clamping position.

21. In a typewriting machine, a platen, a collating table above the platen at the delivery side thereof, consisting of two separate 85 sections adjustable toward and from each other, said sections being cut away in the upper part, a side-edge gage on one of the sections, an adjustable feed-roll bearing against the platen to ride upon the protruding margin of a wide inside sheet, and a clamp on the edge-gage constructed to occupy the least possible space widthwise of the machine, to enable the feed-roll to be located close to the collating table.

HARRY H. VICKERS.
